UNITED STATES PATENT OFFICE.

MABEL BLACKMAN, OF NEW YORK, N. Y., ASSIGNOR TO ARTHUR S. JOSEPH, OF NEW YORK, N. Y.

OVERSHOE FOR HORSES.

Application filed May 5, 1921. Serial No. 466,964.

To all whom it may concern:

Be it known that I, MABEL BLACKMAN, a citizen of the United States, and a resident of the city of New York, borough of Manhattan, county and State of New York, have invented certain new and useful Improvements in Overshoes for Horses, of which the following is a full, clear, and exact description.

10 Among the principal objects which the present invention has in view are: To provide an emergency shoe for preventing a horse from slipping under certain conditions of weather; to increase the frictional hold 15 of the horse's hoof on the surface of the road bed; to increase the life of the frictional element; to provide for substitution of the frictional element by abrasive elements; and to provide simple and quickly 20 applied means for securing the overshoes in service.

Drawings.

Figure 1 is a side view of a horse's hoof 25 equipped with a service shoe and overshoe applied thereto, the same being constructed and arranged in accordance with the present invention;

Fig. 2 is a front elevation of the same, 30 partly in section, the section being cut away to show the interior construction of the overshoe, and its relation to the service shoe;

Fig. 3 is a bottom view of the abrasive element employed in conjunction with the overshoe;

Fig. 4 is a perspective view on reduced scale of the frictional pad with which the shoe is provided;

Fig. 5 is a side view of the horse's hoof 40 showing an overshoe positioned thereon, the overshoe being equipped with frictional and abrasive members constructed and arranged in accordance with the modified form of the invention;

Fig. 6 is a front view of the hoof partly 45 cut away to show the transverse arrangement of the frictional and abrasive elements employed in the modified form of the invention;

Fig. 7 is a perspective view of the abrasive plate used in the modified form of the invention; and

Fig. 8 is a bottom plan view of the plate

for holding the abrasive member shown in 55 Fig. 3 in position when the same is used as a substitute for the frictional element.

Description.

As seen in the drawings, the overshoe 60 here disclosed has a leather boot 14, which is equipped with strap loops 16, best seen in Figs. 1 and 2. Straps 15 permanently attached to the opposite side of the boot are passed through the loops 16 and secured in 65 such position as to draw the rear ends of the boot firmly against the hoof behind the heel or frog thereof. This holds the shoe rigidly on the hoof. The leather conforms readily to the shape of the hoof.

A supporting inturned flange 17 is rigidly secured to the boot by means of a series of riveting clips 18.

As shown best in Fig. 8, the flange 17 has a central opening 19, through which in service the fiber tufts 20 of a mat 21 extend. The mat 21 is retained upon the plate 22 in any suitable manner, the calks 23 and 24 extending through perforations 25 and 26 respectively. When it is desired to dispense 75 with the tufted mat 21, the plate 22 may be used separately. In either event the plate 22 is held in service relation to the flange 17 by cotter-pins 27, which are extended through perforations 28 formed in the said 80 calks 23 and 24, to be exposed below the flange 17 when the said plate is above the 85 said flange.

When thus equipped, it will be seen that the overshoes may be quickly and easily adjusted in service when in an emergency a need for the same arises, it being necessary only to adjust the shoe upon the horse's hoof, and to fasten the straps 15 connecting one side of the opening at the rear of the 95 boot 14 with the loops 16 of the other side of the said opening. Usually the shoes are equipped with the fiber mats 21, particularly if the service is being performed in cities. Should the need arise in the country, however, where it is desired to avoid the clogging of the fibers 20 by the usual mud of the road, the mat 21 is removed and the plate 22 is adjusted so that the calks 23 and 24 extend through to engage the road- 100 bed.

It will be understood that at all times the weight of the horse is borne directly by the

plate 22, which in the preferred form of the invention is in direct contact with the service shoe 29 with which the animal is shod.

In the modified form of the invention shown best in Figs. 5, 6, and 7, a shoe mat 30, the back or body whereof is woven to the shape of the plate 31, is provided. The plate 31 is usually worn outside the flange 17, and is held in service relation thereto by 10 studs 32 which extend through the calk perforations 33 and 34. The cotter-pins 27 are passed through the perforations 35 to hold the plate in service position. The studs 32 extend through to rest upon the service shoe 15 29 to support the weight of the animal. As seen best in Fig. 7, the plate 31 is provided with calks 36 and 37. The calks are preferably somewhat shorter than the tufts 20 of the pad, as can be seen by reference to 20 Fig. 5.

It is obvious that after the animal has been equipped with overshoes, and the need for the use of the same passes, they may be as quickly removed as previously installed.

25 All that is necessary is to release the straps

15 from the loops 16, and to withdraw the shoe from its service position upon the horse's hoof.

Claims.

30

1. An overshoe for horses comprising a boot having a flexible top and rigid bottom; a wearing plate shaped in correspondence with the bottom of said boot; means for removably attaching said plate to said boot 35 for service in connection therewith; and a flexible pad mounted on said plate for engaging the road-bed on which the said overshoe is worn.

2. An overshoe for horses comprising a 40 flexible top and rigid open-centered bottom; a wearing plate shaped in correspondence with the bottom of said boot; means for removably attaching said plate to said boot for service in connection therewith; and a 45 friction pad mounted on said plate for engaging the road, said pad extending through the open center of the bottom of said overshoe.

MABEL BLACKMAN.
